[57] CLAIM

The ornamental design for an acupressure stimulator, as shown and described.

DESCRIPTION

FIG. 1 is a top plan view of an acupressure stimulator, showing my new design;

FIG. 2 is a bottom plan view thereof;

FIG. 3 is a front elevational view thereof, the rear elevational view being identical thereto;

FIG. 4 is a left side elevational view being identical thereto;

FIG. 5 is a cross-sectional view thereof taken along line 5—5 of FIG. 4;

FIG. 6 is a perspective view of the FIG. 1 device; and,

FIG. 7 is a cross-sectional view corresponding to FIG. 5, with adhesive tape and adhered to the back of a hand. The broken line showing of the hand is for illustrative purposes only and forms no part of the claimed design.

FIG. 1**FIG. 2****FIG. 3****FIG. 4****FIG. 5****FIG. 6**

FIG. 7
